STOCKING HANGER

Donald F. Garland, St. Paul, Minn., assignor to Cosom Industries, Inc., Hennepin, Minn., a corporation of Minnesota

Application February 18, 1957, Serial No. 44,903

Term of patent 14 years

(Cl. D33—8)

I claim:

The ornamental design for a stocking hanger, as shown.
